UNITED STATES PATENT OFFICE

2,568,262

HYDRAULIC PRESS CIRCUIT HAVING INTENSIFIER UTILIZED TO DECREASE PRESSURE AND INCREASE VOLUME OR VICE VERSA

Warren R. Tucker, Dayton, Ohio, assignor to H-P-M Development Corporation, Wilmington, Del., a corporation of Delaware

Application November 26, 1945, Serial No. 630,748

1 Claim. (Cl. 60—52)

1

This invention relates to fluid operable apparatus and particularly to fluid operable press operating circuits which include a pressure converter.

The primary object of this invention is to provide an operating circuit for a hydraulic press in which a plurality of operating speeds and working pressures may be obtained from a single fluid source in connection with a pressure converter.

Another object is to provide an operating circuit for a hydraulic press in which the ram may be advanced at high speed to engage the work, thereafter proceed at working speed into the work, thereafter advance still further into the work or dwell on the work at still higher pressures, and to accomplish this without the use of booster rams or surge valves.

It is still another object to provide an operating circuit for a hydraulic press wherein extremely high closing speeds and high working pressures may be had with a simple and relatively small ram without the use of booster rams, surge valves or similar auxiliaries.

These and other objects and advantages become more apparent upon reference to the following specification taken together with the accompanying drawings in which:

Figure 1 is a diagrammatic view of a circuit utilizing a pressure converter as an intensifier;

Figure 2 is a view similar to Figure 1 but showing the converter utilized as a pressure reducer;

Figure 3 is a vertical section through a typical converter and is indicated by a line 3—3 on Figure 4;

Figure 4 is a transverse vertical section through the converter and is indicated by the line 4—4 on Figure 3;

Figures 5, 6, 7 and 8 are transverse sections through the converter and are indicated respectively by the lines 5—5, 6—6, 7—7, and 8—8 on Figure 3;

Figure 9 is a diagrammatic view of a press circuit utilizing a pressure converter according to this invention;

Figure 10 is a view of a modified valve structure adapted for being used in connection with the circuit of Figure 9;

Figure 11 is a partial circuit illustrating automatic control means for shifting the valves; in 50 the circuits of Figures 9 and 10;

Figure 12 is an electrical diagram for use in connection with the control circuit of Figure 11; and

Figure 13 is a view of the motor of Figure 9 55

2

and the manner of associating with it the several control switches of the circuit of Figure 12.

General arrangement

According to this invention the discharge of fluid from a source is divided into increments of volume in the pressure and flow converter, the increments are modified in quantity through a connection with exhaust, and the modified increments are then discharged to a motor or similar hydraulic auxiliary.

If the volume of the increments are reduced by exhausting a portion thereof to exhaust, the energy of the exhausted portion is utilized in compressing the remainder to a higher pressure so that the product of volume and pressure at the inlet of the converter is substantially equal to the production of volume and pressure at the outlet.

20 If the increments are increased by the connection with the exhaust, then the fluid which is discharged from the converter is at a lower pressure and at a correspondingly greater volume.

Referring to Figure 1, for purposes of explanation there is diagrammatically illustrated the action of a single piston-cylinder unit, the pressure converter when it is utilized for intensifying pressure and which, as hereinafter described, comprises a plurality of such units which are alternately controlled by a common valve means. 25 In this figure a pump 10 draws fluid from a reservoir 12 through a conduit 14 and discharges fluid under pressure into a conduit 16. The flow in the conduit 16 is divided by a valve member, not shown in Figs. 1 and 2, in the branch conduits 16' and 16'' which communicate, respectively, with the chambers 18 and 20 of the single piston-cylinder unit generally indicated at 22'.

This unit of the pressure converter comprises a cylinder 24 which has a central portion within which is reciprocable the piston 26 and the reduced diameter end portions within which are reciprocable the pistons 28 and 30. The piston 26 reciprocates in the chamber 18 while the piston 30 reciprocates in the opposite end chamber indicated at 32. The piston 26 divides the central portion of the cylinder 24 into the opposite end chambers 18 and 32.

The chamber 34 is connected by a conduit 36 with the reservoir 12 while the chamber 32 is connected by a conduit 38 with the inlet of a motor 40. The other side of the motor 40 may be connected by a conduit 42 with the reservoir 12 for returning exhaust fluid thereto.

As illustrated in Figure 1, the pump is supply-

ing fluid to both of the upper working areas of the pistons 26 and 28 while the lower working areas are connected one with the motor inlet and the other with exhaust. Thus, the pressure delivered to the motor 40 is augmented over the pressure delivered by the pump by the ratio of the said upper areas to the area which is connected to the motor inlet. By apportioning the sizes of the pistons, any desired intensification of pressure may be had.

Figure 2 is a similar diagrammatic illustration of a single cylinder-piston unit wherein the circuit is modified to utilize the unit 22' as a pressure reducing, and a flow augmenting device. In this view, the discharge conduit 16 of the pump 10 is connected to the chamber 18, the chamber 20 is connected by a conduit 44 with the reservoir 12, the chamber 32 is connected by a conduit 38 with the inlet of the motor 40 and the chamber 34 is connected by a conduit 46 with the conduit 38.

In Figure 2, the pressure supplied to the motor is decreased below that supplied by the pump by the ratio of the two lower working areas to the area supplied by the pump. As in the case of the system shown in Figure 1, only one of a plurality of cylinder-piston units is disclosed for sake of clarity, it being understood that the complete converter, as will hereinafter be described, comprises a plurality of these piston-cylinder units and a valve means operable continuously to alternate the flow of fluid from one end of the cylinders to the other to reciprocate the pistons so that a continuous flow of fluid results.

In Figure 1, it will be noted that a portion of the fluid previously supplied by the pump to one of the lower areas of the piston is discharged to exhaust, and that the energy thereof was utilized for pressurizing fluid previously supplied by the pump to the chamber 18. It will be noted in connection with Figure 2 that the supply of fluid from the pump to the converter is being augmented by a further supply from the exhaust and that a portion of the energy in the fluid from the pump is utilized to compress the fluid so supplied from exhaust on the previous piston stroke to a higher pressure.

Pressure and flow converter

The fluid-pressure-volume converter or fluid intensifier 22 is more particularly shown in Figures 3 through 8 and is fully shown and described in my United States Patent Number 2,486,079, issued October 25, 1949, entitled "Hydraulic Booster."

The fluid-pressure-volume converter comprises a cylinder block 50 which has a plurality of axial bores 52 circumferentially spaced about a central bore 54. The bores 52 provide cylinders within which reciprocate the pistons 56 having the oppositely extending reduced piston portions 58 attached thereto. The portions 58 reciprocate in bored cylindrical plugs 60 which are inserted from opposite ends of the block 50 into somewhat enlarged end portions of the bores 52. The piston 56 and the rods 58 define the upper working areas indicated at A and B and the lower working areas indicated at C and D. The working areas are connected by radial passages with the central bore 54 of the block 50 at different levels.

Within the bore 54 is mounted a valve member indicated at 62 which is supported on the anti-friction bearings 64 and which has an operating shaft 66 whereby the valve member may be rotated. The block 50 has port 68 (Figure 4) and

the valve member 62 has a groove 70 at the level of the said port. The groove 70 is communicated with the levels of the connections to the areas A and B by a pair of oppositely disposed notches 72 which extend somewhat less than 90° about the periphery of the said valve member. The levels of the connections to the areas C and D are communicated with the groove 70 by a pair of oppositely disposed notches 74 which are similar to the notches 72 but which are disposed at 90° therefrom.

The valve member comprises the groove 76 at the upper end thereof and the groove 78 at the lower end thereof which communicate by a bore 80 with port 82 in the block 50. The groove 76 communicates with the level of the connection with the area A by means of the oppositely disposed notches 84 which are disposed at 90° from the notches 72 so that alternate communication may be had with the area A. The groove 78 is similarly provided with the notches 86 which are disposed at 90° from the notches 84.

Arranged at the level of the connection with the area B are the oppositely disposed flats or notches 88 which are disposed at 90° from the notches 72 so that the said notches will alternately communicate with the area B. The notches 88 are connected by radial bores with the central passage 90 in the valve member which communicates directly with an exhaust conduit 92. At the level of the connection with the area C are similarly arranged notches 94 which communicate with the central passage 90 and which are disposed at 90° from the notches 88.

It will be apparent that the rotation of the valve member 62 is effective first to connect the port 68 to the areas C and D while connecting area B to the exhaust 92 and the area A to the port 82 and thereafter to reverse the said connections; that is to connect A and B to the port 68, C to exhaust and D to the port 82. It will also be apparent that by providing a plurality of cylinders and pistons, the same will operate to receive and to discharge fluid in overlapping increments so that substantially continuous operation may be had.

By connecting the pump to the port 68, the converter 22 acts as a pressure intensifier, and by connecting the pump the port 82, the converter acts as a pressure reducer. In either case, the efficiency of conversion is high and the energy of the working fluid, represented by the production of pressure and volume, is substantially the same at the inlet and outlet ports of the converter.

Operating circuit of Figure 9

In Figure 9, there is illustrated an upward acting ram 100 having an advancing means 102, a retracting means 104 and reciprocably mounted in a cylinder 106. The advancing and retracting means are connected with the service ports of the four-way reversing valve 108 which receives fluid from a conduit 110 and which has an exhaust connection 112.

The conduit 110 is connected with one of the ports of a four-way distributing valve 114 which also has connected therewith the conduits 116, 118, and 120. The conduit 116 is connected with the discharge side of a pump 122 which draws fluid from a reservoir through a conduit 124. The conduit 118 connects with the port 68 of the converter 22 and the conduit 120 connects with the port 82.

The distributing valve 114 includes the valve member 126 movable to connect the conduits 116

and 118 and the conduits 110 and 120 or, to connect the conduits 116 and 120, and the conduits 110 and 118. In the first position, the converter acts as a pressure reducer and delivers an augmented quantity of fluid to the conduit 110 and, in the second case the converter acts as a pressure intensifier and delivers a reduced volume of fluid at intensified pressures to the conduit 110.

For rotating the valve member 62 of the converter 22, there is provided the electric motor 128 which is connected with the shaft 66 and which operates continuously to rotate the valve member for effecting the aforementioned connections to the reciprocating pistons in the converter.

In Figure 10, there is illustrated a valve which provides for a third pressure for actuating the motor by the passage 130 which is operable directly to connect the conduits 116 and 110 when the valve member is in a predetermined position. By means of the valve passage shown in Figure 10, there is available for actuating the motor a low pressure large volume flow when the converter is connected as a pressure reducer, a medium volume medium pressure flow when the pump is directly connected with the passage 130, and a low volume high pressure flow when the converter is connected to act as a pressure intensifier. The ram 100 may thus be advanced at high speeds, perform work at medium working speeds and finally dwell or do further work at intensified pressure.

Control circuit of Figures 11 and 12

For obtaining an automatic cycle of operations of the work ram 100, there may be provided the circuit shown in Figure 11 which is controlled by the electrical circuit of Figure 12.

In Figure 11, the conduit 116 from the pump is connected with the inlet port 200 of a valve 202 which has a rotatable valve member 204. As the valve member 204 rotates counterclockwise, communication is successively established between the pressure port 200 and the conduits 120, 110, and 118. The valve member 204 comprises the notches 206 and 208, the first of which connects the conduits 110 and 118 when the port 200 is in communication with the conduit 120, and the second of which connects the conduits 110 and 120 when the port 200 is in communication with the conduit 118.

In Figure 11, the four-way valve 108 is continuously urged by a spring 210 into position to connect conduit 110 with the ram retracting means and is adapted for being moved into position to connect the conduit 110 with the ram advancing means by the energization of the solenoid S1.

For shifting the valve member 204 into its several positions, there is provided a ratchet wheel 212 which has teeth that may be engaged by a pawl 214 when the latter is moved leftwardly by energization of a solenoid S2. The ratchet wheel and, therefore, the valve member 204 are continuously urged clockwise by a torsion spring 216 and are retained in any of their operative positions by a latch bolt 218. The latch bolt may be withdrawn at any time by the energization of a solenoid S3 so that the torsion spring 216 may return the valve member to its Figure 11 position.

For controlling the actuation of the solenoids S1, S2 and S3, the circuit of Figure 12 is provided. In Figure 12, there is connected between the power lines L1 and L2 a contactor coil A

in series with the normally closed contactor blades B2, and the normally open starting switch 220. The starting switch is bypassed by the normally open blades A1 of the contactor A and the normally open limit switch LS1. The blades A1 provide a holding circuit for maintaining the contactor A energized, and the limit switch LS1 is located to be closed by the ram 100, as shown in Figure 13, in its fully retracted position for giving a full automatic cycle when desired.

Also connected between L1 and L2 is the solenoid S1 in series with the normally open blades A2. The energization of A will close the blades A2 and energize S1 to shift the valve 108 to direct actuating fluid to the ram advancing means. At this time the valve member 204 occupies its Figure 11 position and the ram 100 advances at a rapid rate and under low pressure.

When the ram has advanced a predetermined amount, it may engage and temporarily close a limit switch LS2 which will energize S2 to actuate the pawl 214 to advance the ratchet wheel 212 and the valve member 204 to their next position. This connects the pump directly with the ram advancing means and the speed of the ram is reduced and the operating pressure available is correspondingly increased. Optionally, there may be provided a pressure switch connected with the advancing means and indicated at T1 which is temporarily closed in response to a predetermined pressure acting on the ram for energizing the solenoid S2.

In response to a further advance of the ram 100, the solenoid S2 is energized again to index the valve member 204 to its third position by the temporary closure of a limit switch LS3. There may also be operated the pressure switch T2 which is temporarily closed in response to a higher pressure than the pressure which actuates T1 for energizing S2. The ram 100 now advances at a still lower speed with a still higher working pressure available.

In order to halt the working stroke of the ram 100, there is provided a limit switch LS4 which is closed when the ram has advanced a predetermined amount and energizes a contactor coil B. Optionally, the coil B may be energized by the closure of a pressure switch T3 connected with the ram advancing means. Energization of B closes the blades B1 thereof and energizes the solenoid S3 to withdraw the latch bolt 218 from engagement with the ratchet wheel 212 to permit the torsion spring 216 to return the valve member 204 to its Figure 11 position. Simultaneously, the blades B2 open, deenergize A and thus deenergize S1 to permit the spring 210 to move the valve 108 into position to connect the conduit 110 with a ram retracting means. The ram is thus retracted at high speed to its Figure 9 position.

The general arrangement of the ram 100, the limit switches LS1, LS2, LS3, and LS4; and the pressure switches T1, T2, and T3 is shown in Figure 13.

It will be apparent that the automatic control circuit of Figure 11 and the electrical diagram of Figure 12 will present only one of many combinations that may be had by employing the converter 22 for intensifying fluid pressures or for augmenting fluid flows.

By utilizing the principles of this invention a hydraulic press may be constructed which has a rapid advancing speed, a first working speed and pressure, and a second working speed and pressure, all of which may be had with a simple ram of relatively small size. This eliminates the cost

of booster rams, surge valves, permits the ram to be made substantially smaller for any given working tonnage, and does so without sacrificing efficiency or flexibility of the apparatus.

It will be understood that this invention is susceptible to modification in order to adopt it to different usages and conditions and, accordingly, it is desired to comprehend such modifications within this invention as may fall within the scope of the appended claim.

I claim:

In a hydraulic control circuit; a differential fluid motor having oppositely disposed pressure areas; a reversing valve having a fluid inlet and an exhaust outlet and a pair of service ports connected respectively with the oppositely disposed pressure areas of said motor and operable selectively to direct fluid introduced within the fluid inlet to either of the pressure areas of said motor while connecting the opposite area to exhaust; a fluid displacement pump; a fluid pressure-volume converter having first, second and exhaust ports and a rotary valve member; motor means drivingly connected with the valve member of said converter for rotating the latter, said converter being operable upon rotation of the valve member and upon the introduction of pressure fluid into either the first or second port to discharge pressure fluid at a modified pressure-volume ratio from the opposite port; valve means having connections respectively with said pump, the first and second ports of said converter and the inlet port of said reversing valve and having a valve member therein movable to a first posi-

tion connecting said pump with the first port of said converter while connecting the second port of said converter with the inlet port of said reversing valve, and a second position connecting said pump with the second port of said converter while connecting the first port of said converter with the inlet port of said reversing valve; and means responsive to fluid pressures within said fluid motor and connected with the movable valve member of said valve means for moving the latter between said first and second positions.
